Edward Pancotti, Bronxville, N. Y.

Application June 15, 1955, Serial No. 36,526

Term of patent 14 years

(Cl. D56—1)

Fig. 1

Fig. 2

Fig. 1 is a partly perspective top view of a grill showing my new design as incorporated in an accordion, part of which is shown in outline.

Fig. 2 is a top plan view of the grill as shown in Fig. 1. The broken lines shown in the drawings are for illustrative purposes only.

I claim:

The ornamental design for an accordion grill, substantially as shown and described.
